UNITED STATES PATENT OFFICE.

ELLERY PERRY, OF OLEAN, NEW YORK, ASSIGNOR OF ONE-HALF TO ROY E. VANCE,
OF OLEAN, NEW YORK.

DESIGN FOR A CASING FOR A RAILROAD-CROSSING DANGER SIGNAL.

Application filed February 7, 1925. Serial No. 12,297. Term of patent 7 years.

To all whom it may concern:

Be it known that I, ELLERY PERRY, a citizen of the United States, residing at Olean, in the county of Cattaraugus and the State of New York, have invented a new, original, and ornamental Design for Casing for a Railroad-Crossing Danger Signal, of which the following is a specification, reference being had to the accompanying drawing, forming part thereof.

The figure is a perspective view of the casing for a railroad crossing danger signal, showing my new design.

I claim:

The ornamental design for a casing for a railroad crossing danger signal, as shown.

ELLERY PERRY.
